UNITED STATES PATENT OFFICE.

GEORGE A. POWELL, OF FOREST HILLS GARDENS, NEW YORK.

DOORCHECK.

Application filed December 16, 1927. Serial No. 240,507.

My invention has for its object a particularly simple door check for holding a door in any desirable open position or in its closed position, and which is cheaply and easily manufactured and is highly efficient and durable in use. Other objects will appear throughout the specification.

In describing this invention, reference is had to the accompanying drawing in which like characters designate corresponding parts in all of the views.

Figure 1 is a fragmentary sectional view illustrating my device as used between the bottom of a door and the floor.

Figure 2 is a bottom plan view thereof.

My invention comprises generally, a wedge shaped member of fibrous material for coacting between the bottom of a door and the floor, the thick end of said wedge being provided on the lower face thereof with a rectangular shaped opening extending into said wedge and a member of flexible material fixed in said opening and extending beyond said lower face for frictionally engaging

the floor.

In the drawing, 1 represents a door and 2 the floor. 3 represents the body of my door check which may be of any desirable size or shape, but is preferably wedge shaped. This body portion may be of any desirable material, but is preferably formed of wood.

4 is the member for flexibly and frictionally engaging the floor 2. This member may be of any desirable material as felt, rubber or the like and may be fixed to the body or wedge 3 in any desirable manner.

As here shown, the rear or thick end of the body or wedge is formed with a rectangular shaped opening 5 in the lower face thereof and a piece of rubber of the same general shape but preferably slightly larger, is compressed therein with a portion thereof extending beyond the lower face of said body or wedge 3.

If desirable, the member 4 may be glued or cemented in said opening 5.

In use, the door 1 is placed in the desired open position and the small or pointed end of the wedge shaped body 3 is forced between the bottom thereof and the floor 2 with the rubber member 4 frictionally engaging the floor and compressed between the floor and the lower face of the wedge 3.

This wedge may also be used to keep the door from rattling when in a closed position.

What I claim is:

A door check comprising a wedge shaped member of fibrous material for coacting between the bottom of a door and the floor, the thick end of said wedge being provided on the lower face thereof with a rectangular shaped opening extending into said wedge and a member of flexible material fixed in said opening and extending beyond said lower face for frictionally engaging said floor.

In testimony whereof, I have hereunto signed my name at Syracuse, in the county of Onondaga, and State of New York, this 21st day of November, 1927.

GEORGE A. POWELL.
